UNITED STATES PATENT OFFICE.

GEORGE URBAN, JR., OF CHEEKTOWAGA, NEW YORK.

CARTON.

Application filed April 1, 1924. Serial No. 703,426.

This invention relates to improvements in cartons, and more particularly to cartons of the kind adapted to contain a plurality of packages or other articles.

The principal objects of the invention are to construct a carton of this sort to meet the aforesaid requirements by providing a frame member adapted to surround the sides and ends of a group of packages or articles so as to confine them therein as a unit, and to provide a folder adapted to be attached to the opposite ends or sides of said frame, and which has a panel adapted to extend across one of the frame openings to engage the packages or articles in the frame, said folder further cooperating with an outer sheath to protect the packages or articles during shipment; also to construct the frame and folder so that, when they are removed with the goods from said outer sheath, the packages may be displayed through the uncovered opening of the frame, while the parts of the cartons are nevertheless left in tact, and may be used again as a protector for the articles.

Another object of the invention is to provide a construction whereby two of the folders may be connected together so as to hinge one on the other so that each of the folders may be secured to a frame member containing a group of packages or articles, permitting the folders to be disposed so as to display the faces of the two groups of packages in the frame, and so that the folders may be swung on their hinge connection to bring the exposed faces of the packages in each frame face to face and in contact and, when so arranged, to form an enclosure for the packages which may be slipped into an outer sheath to completely enclose the packages and protect them for shipment or storage.

Another object of the invention is to construct a carton adapted to meet all the aforesaid requirements and in which the various parts may be folded flat for storage or shipment before use, and which may be manufactured at a cost comparing favorably to that of previous forms of cartons which are not adapted for the combined use of a shipping carton and a display carton; also to provide a carton for the purposes stated which may be assembled and the goods packed therein as quickly as the usual protecting and shipping cartons at present in use.

Other objects of the invention are to im-

prove cartons of the sort mentioned in other respects hereinafter specified.

In the accompanying drawings:

Fig. 1 is a perspective view of a frame member, a double folder, and an outer sheath respectively, of a carton constructed in accordance with the preferred embodiment of the invention.

Fig. 2 is a perspective view of one of the frame members engaging a group of packages, one of the packages being separated from the group.

Fig. 3 is a longitudinal section of the carton completely assembled and containing a plurality of packages.

Fig. 4 is a side elevation showing two folder members connected together and being attached to two of the frame members of the carton.

Fig. 5 is a perspective view thereof, showing the assembled frames and hinged folders disposed for displaying the packages contained in the frames.

Fig. 6 is a fragmentary perspective view of the hinged folders and their enclosed frame members, folded together and partly withdrawn from the outer sheath of the carton.

The carton of this invention is preferably made of the usual double faced corrugated board, but the carton could be formed of other suitable material. The carton comprises one or more rectangular, open frame members so formed that each frame is adapted to fit snugly around a group of rectangular packages or articles, to form, in effect a single unit. A folder or wrapper is also provided for each frame which is adapted to be secured, preferably to the ends of the frame, and which has a part extending across one of the open sides of the frame in contact with the packages therein, while the other side of the frame remains open and permits an unobstructed view of the packages in the frame and allows them to be removed therefrom as required, without disturbing the frame or the folder. An outer sheath or tube of rectangular cross section is provided, into which one or more of the frames and attached folder or folders, and the contents are adapted to snugly fit, to make up the completed package, such that the goods may be safely shipped or stored.

The carton is adapted to contain a plurality of rectangular articles or packages A, preferably of the same size, and the use of

the improved carton enables a manufacturer to supply a variety of different goods in a single carton. For instance, a milling concern may provide a set of packages, each 5 containing a different product such as flours and cereals, in compact, available form for the consumer and arranged in the carton, so that, by removing the outer sheath, the retailer may exhibit the selection of goods 10 without removing them from the inner carton members or deforming these parts. The inner members, with the packages, may be returned to the sheath at any time, either for shipment, or for sale.

15 In the particular arrangement shown in the drawings, two frame members 10 are shown, each of which is adapted to contain four of the packages A, but the frames may be formed to contain any other number of 20 packages. Each frame 10 is preferably made of a single strip of the material bent or folded to provide two side panels 11 and two end panels 12, and the two ends of the strip are preferably permanently secured 25 together in any suitable manner. The frames 10 are normally collapsed as shown in Fig. 1 to occupy the minimum space, and when required for use, the desired number 30 of the packages are placed side by side with their top and bottom edges in alinement, and a frame member is opened up to rectangular form and slipped around the group of packages, with the side panels 11 engaging 35 the top and bottom faces of the packages, and the end panels engaging the outer sides of the two end packages, see Fig. 2. The height or vertical transverse dimension 40 of the panels 11, 12 of the frames is preferably substantially equal to the thickness of the packages A, so that when the frame is in place only the faces of the packages are exposed, thus providing a substantially rectangular unit 13.

A folder B is provided for each frame 45 and its contents. As shown, each folder B is made of a strip of the material, preferably as wide as the length of the packages in the frame, and bent to form a rectangular back panel 14, of substantially the 50 length of the unit 13, and having opposite end flaps or parts 15, 16. To apply a folder to a frame, the back panel 14 is laid flat on a support, and the frame 10 and its packages are placed on the panel so that the panel 55 will extend across and substantially close one of the frame openings and engage the faces of the packages. The flaps 15, 16 are then secured to the end panels 12 of the frame, as by applying a suitable adhesive 60 to the flaps and folding them against the panels, see Figs. 4 and 5.

In the particular embodiment shown in the drawings, two of the folders B are hinged or connected together, as at 18, the

hinge being preferably formed by making 65 the two folders from a single strip of material and creasing it along the line of connection of the adjacent flaps 16, 16. By this arrangement the two connected folders B may be attached to the frames 10, by placing 70 two frames with the articles arranged therein upon one of the panels 14 of the folder, and then placing the folder over the two frames so that the other panel 14 thereof closes the upper face of the upper frame, 75 and then gluing or cementing the end flaps 15 and 16 to the ends of the frames. In this manner the packages A are completely enclosed and protected by the frames 10 and folders B, and a rectangular unit is provided 80 which is adapted to be inserted into an outer sheet C of usual form having four side walls 20 and opposite open ends. Thus the packages A are protected at the opposite 85 ends of the carton by two thicknesses of material comprising the end panels 12 and flaps 15 or 16, while the side walls 20, back panels 14 and side panels 11 form a double 90 thickness at the sides of the carton, see Fig. 3.

When it is desired to display the packages contained in the carton, the sheath C is removed and the two folders B are swung apart as shown in Fig. 5, on the hinge 18, to expose the inner opposed and unobstructed 95 faces of the packages in the two frames 10.

While the invention is illustrated in connection with two attached folders B, one frame 10 and a single folder B may be used 100 with good results, in which case a sheath formed to fit the single unit may be provided, or a number of such units may be arranged to slip into a sheath of suitable 105 dimensions.

I claim as my invention:

1. In a carton adapted to support a plurality of articles in rows arranged face to face, the combination of a pair of open sided frames in which the articles are arranged in rows, said frames being placed together with an open face of each frame facing an open face of the other frame, a folder surrounding said frames and extending around the opposite open faces thereof, and an open ended sheath into which said folder with the frames arranged therein is inserted endwise, each end of the folder being secured to one end of each frame.

2. A carton according to claim 1 characterized in that the intermediate portion of the folder is scored to facilitate bending thereof and the portions of the folder adjacent to the scored portion are secured to the other ends of the frames, to form a hinged connection between the two frames.

GEORGE URBAN, JR.
